APPAREL GARMENT AND METHOD FOR
MAKING THE SAMEMilton G. Rosenfeld, Ladue, Mo., assignor to
Western Garment Company, St. Louis, Mo., a
corporation of Missouri

Application June 29, 1951, Serial No. 234,396

6 Claims. (Cl. 2-93)

1

This invention relates in general to certain new and useful improvements in apparel garments and methods for making the same.

In the manufacture of women's suits it has become quite fashionable to design coats or jackets which are unlined or skeleton lined, as it is sometimes called. These garments are comparatively light in weight and serve an extremely useful purpose in the average woman's wardrobe inasmuch as such garments are adapted for use practically on a year round basis, being light enough in weight to be worn on most summer days and being extremely comfortable and easy to wear beneath coats and other heavier outer wraps in the winter. Such garments, however, present serious manufacturing problems. In order to provide adequate rigidity to the front panels and lapels of the garment it is necessary to use some type of stiff fabric, such as goats hair, cambric, or the like. These materials, such as goats hair and the like, are somewhat coarse fibered and usually are used in white or light colors. Consequently, when the panel of goats hair fabric is employed in the front construction of the garment, the light colored goats hair will be visible around the edges of the buttonholes and produce a very unsightly appearance. Efforts have been made to overcome this difficulty by dyeing the goats hair to match the fabric of the garment. This expedient, in addition to being expensive, is unsatisfactory because the goats hair is of such markedly different texture from the garment-fabric that it will not take the dye in the same manner and hence is readily distinguishable and still presents an unsightly appearance around the buttonholes. Of course, it is possible to use various types of unconventional buttonhole constructions which are known in the dressmaking and tailoring art, but such button-hole constructions are not considered fashionable or well tailored and add greatly to the expense of the garment while not improving the appearance thereof. On the other hand, it is not possible to eliminate the goats hair lining entirely and substitute a fabric which more nearly matches the fabric of the garment because the rigidity imparted to the garment by the goats hair liner is vitally necessary in the region of the collar and lapel, otherwise the garment will not hold its shape during wear, but will quickly become slack and shabby in appearance.

It is, therefore, the primary object of the present invention to provide a garment having a facing liner formed of the same material as the other panels of the garment which facing liner

2

is uniquely combined with an upper section of goats hair adapted to impart proper firmness and rigidity to the collar and lapel sections of the garment.

It is another object of the present invention to provide a garment of the type stated in which the various seams employed in joining the several parts are uniquely arranged so as to provide a smooth uniform leading edge which does not present bumps or press marks revealing the presence of underlying seams.

It is a further object of the present invention to provide a garment of the type stated and the method of making the same which is simple and economical.

With the above and other objects in view, my invention resides in the novel features of form, construction, arrangement, and combination of parts presently described and pointed out in the claims.

In the accompanying drawings—

Figure 1 is a plan view of the facing liner in a preliminary stage of construction;

Figure 2 is a plan view of the finished facing liner;

Figure 3 is a fragmentary sectional view taken along line 3—3 of Figure 2;

Figure 4 is a plan view of the facing liner with a section of tape stitched along one end;

Figure 5 is a plan view of the facing;

Figure 6 is a fragmentary plan view of the facing and facing liner preliminarily secured together along one edge;

Figure 7 is a transverse sectional view taken along line 7—7 of Figure 6;

Figure 8 is a plan view of one of the front panels of the garment;

Figure 9 is a fragmentary sectional view showing the front panel secured to the facing in an intermediate stage of construction;

Figure 10 is a transverse sectional view showing all of the several elements of the front section of the garment secured together in the inside-out relation in which they are at the conclusion of all the sewing operations;

Figure 11 is a front plan view of the front panel of the garment after it has been stitched together and turned right side out;

Figure 12 is a transverse sectional view taken along line 12—12 of Figure 11; and

Figure 13 is a front elevational view of the finished garment embodying the construction of the present invention.

Referring now in more detail and by reference to the drawings, which illustrate a

3

preferred embodiment of the present invention, 1 designates a facing section formed of the same material as is used for the other parts of the garment. Superimposed flatwise upon the forward face of the facing liner with its forward face presented downwardly upon the forward face of the facing section 1 is a section of goats hair 2. The sections 1 and 2 are secured together along their matching edges by a line of stitches 3 in the provision of a simple seam 4 having upturned flaps 5, 6, to form a complete facing liner 7, as best seen in Figures 2 and 3. In this connection it should be noted that for purposes of description the term "forward" will be used at all times to refer to the faces of the various panels which are presented outwardly away from the body of the wearer when the garment is being worn and the term "rearward" will be applied to opposite faces of such panels, that is to say, those faces which face inwardly toward the body of the wearer when the garment is being worn. These terms will be respectively applied to the various faces of the panels whether or not, in the actual construction of the finished garment, these panels and their respective faces are visible or not.

Stitched flatwise to the completed facing liner 7, is a narrow section of tape *t* which projects laterally outwardly beyond the edge of the facing liner 7, as shown in Figure 4. Cut out of a suitable section of the fabric from which the garment is being made is a facing panel 8 substantially similar in shape to the facing liner 7 having a lapel-forming notch 9 matching the lapel-forming notch 10 of the facing liner 7 and having a leading edge 11 conforming in shape to the leading edge 12 of the facing liner. The facing panel 8 is, however, approximately three quarters of an inch wider than the facing liner 7 so that when the two panels are laid one on top of the other with their inner edges 13, 14, disposed in overlying registration the leading edge 11 will extend outwardly beyond the leading edge 12 and the exposed marginal edge of the tape *t*. The facing panel 8 is laid down with the facing liner 7 superimposed thereon so that the rearward face of the facing panel 8 is in abutting relation against the forward face of the facing liner, or, in other words, the two panels are placed together in inside-out relation. The panels 7, 8 are thereupon joined together along their inner margins by a line of stitches 15, substantially as shown in Figures 6 and 7.

A front panel 16 is cut out of the fabric from which the garment is to be made and is laid down with its forward face in flatwise abutment upon the rearward face of the facing panel 8 and its leading edge 17 projecting outwardly beyond the leading edge 11 of the facing panel 8, the facing liner 7 being pulled back loosely out of the way, substantially in the manner as shown in Figure 9. The front panel 16 and facing panel 8 are then jointed together by a line of stitches 18.

Thereupon, the facing liner 7 is pulled back into overlying relation upon the curled-up front panel 16 so that the outer or exposed margin of the tape *t* is in registration with the leading edge 17 of the front panel 16 and the tape is secured to the projecting portion of the body panel 16 by a line of stitches 19, substantially as shown in Figure 10. It will be noted by reference to Figure 10 that the entire front panel of the garment which is now completely stitched together is disposed in inside-out relationship and the fullness which is indicated at *x* in Figure 10 is due to the greater width of the facing panel 8.

4

with respect to the facing liner 7, as previously pointed out.

The several panels, as thus jointed together, are then turned completely inside-out and pressed to form a completed front body element *b*, as shown in Figure 11. This body element *b* may be duplicated in substantially mirror-image form to provide the matching front body panel *b'* and stitched to conventional sleeve, back and collar elements to form a finished jacket, as shown in Figure 13. The garment is then conventionally provided with any desired number of buttons and buttonholes.

It will be noted that the seams adjacent to the leading edge 1 of the finished garment, as best seen in Figure 12, are extremely flat and compact so that the front of the garment will be smooth and attractive in appearance. In this connection it should be particularly noted that in the region of the seam 4 between the goats hair section 2 and the facing section 1, the finished garment has the same number of thicknesses or plies of material across both sides of the vertical juncture line *y*. Since the facing liner section 1 is thus made of the same fabric as the rest of the garment the buttonholes will not show any unsightly off-color edges and, at the same time, a section of goats hair lighting material will thus be incorporated in the area of the garment where it is actually needed.

It should be understood that changes and modifications in the form, construction, arrangement, and combination of the several parts of the apparel garment and methods for making the same may be made and substituted for those herein shown and described without departing from the nature and principle of my invention.

Having thus described my invention, what I claim and desire to secure by Letters Patent is—

1. A ladies' suit jacket comprising front panels, facing panels marginally secured to the front panels, said facing panels being formed of the same material as the front panels, and an intermediate lining section interposed between the front panels and facing panels, said lining section consisting of a lower portion and an upper portion, the upper portion being formed of stiff, coarse material and the lower portion being formed of the same material as the front and facing panels.

2. A ladies' suit jacket comprising front panels, facing panels marginally secured to the front panels, said facing panels being formed of the same material as the front panels, and an intermediate lining section interposed between the front panels and facing panels, said lining section consisting of a lower portion and an upper portion stitched together transversely, the upper portion being formed of stiff, coarse material and the lower portion being formed of the same material as the front and facing panels.

3. The method of making a suit jacket which comprises cutting out a front panel, cutting out a facing panel, cutting out a lining panel, each of said panels respectively having front and rear margins, stitching a length of tape along the front margin of the lining section, laying the lining panel and facing panel upon each other with their outside faces in overlying abutment and their rear margins in registration, stitching the facing and lining panels together along their rear margins, laying the outside face of the front panel against the outside face of the facing panel with the front margin of the front panel projecting beyond the front margin of the

facing panel, rolling the front panel up lengthwise compactly so as to lie entirely between the front and rear margins of the facing panel, laying the lining panel over the rolled-up front panel and stitching the projecting marginal portions of the tape and front panel together to form an elongated open-ended tube which is wrong side out, and finally turning the tube inside out.

4. The method of making a suit jacket which comprises cutting out a front panel, cutting out a facing panel, cutting out a lining panel, each of said panels respectively having front and rear margins, stitching a length of tape along the front margin of the lining section, laying the lining panel and facing panel upon each other with their right sides in overlying abutment and their rear margins in registration, stitching the facing and lining panels together along their rear margins, laying the right side of the front panel against the right side of the facing panel with the front margin of the front panel projecting beyond the front margin of the facing panel, rolling the front panel up lengthwise compactly so as to lie entirely between the front and rear margins of the facing panel, laying the lining panel over the rolled-up front panel and stitching the projecting marginal portions of the tape and front panel together to form an elongated open-ended tube which is wrong side out, and finally turning the tube inside out.

5. The method of making a suit jacket which comprises cutting out a front panel, cutting out a facing panel, cutting a lower lining section of material matching the material of the front panel, cutting an upper lining section of relatively stiff material, seaming said sections together along transverse margins to form a lining panel conforming in shape to the facing panel, each of said panels respectively having front and rear margins, stitching a length of tape along the front margin of the lining section, laying the lining panel and facing panel upon each other with their outside faces in overlying abutment and their rear margins in registration, stitching the facing and lining panels together along their

rear margins, laying the outside face of the front panel against the outside face of the facing panel with the front margin of the front panel projecting beyond the front margin of the facing panel, rolling the front panel up lengthwise compactly so as to lie entirely between the front and rear margins of the facing panel, laying the lining panel over the rolled-up front panel and stitching the projecting marginal portions of the tape and front panel together to form an elongated open-ended tube which is wrong side out, and finally turning the tube inside out.

6. The method of making a suit jacket which comprises cutting out a front panel, cutting out a facing panel, cutting out a lining panel conforming in shape to the facing panel, each of said panels respectively having front and rear margins, stitching a length of tape along the front margin of the lining section, laying the lining panel and facing panel upon each other with their outside faces in overlying abutment and their rear margins in registration, stitching the facing and lining panels together along their rear margins, laying the outside face of the front panel against the outside face of the facing panel with the front margin of the front panel projecting beyond the front margin of the facing panel, rolling the front panel up lengthwise compactly so as to lie entirely between the front and rear margins of the facing panel, laying the lining panel over the rolled-up front panel and stitching the projecting marginal portions of the tape and front panel together to form an elongated open-ended tube which is wrong side out, and finally turning the tube inside out.
